CLAIM

The ornamental design for a latch assembly, as shown and described.

DESCRIPTION

FIG. 1 is a front, top and right side perspective view of our design for a latch assembly;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a plan view thereof; and,

FIG. 7 is a bottom view thereof.

The broken line environmental showing in FIGS. 1-6 is for illustrative purposes only and forms no part of the claimed design.
